US0D1080536S

(12) **United States Design Patent** (10) **Patent No.:** **US D1,080,536 S**
(45) **Date of Patent:** **** Jun. 24, 2025**

(54) **WIRELESS CHARGER**

(71) Applicant: **JIANGSU AUSTIN Optronics TECHNOLOGY CO., LTD.**, Jiangsu (CN)

(72) Inventors: **Jing Ling**, Nanjing (CN); **Xiaodong Zhai**, Nanjing (CN); **Peng Zhao**, Nanjing (CN); **Bin Jiang**, Nanjing (CN)

(73) Assignee: **JIANGSU AUSTIN Optronics TECHNOLOGY CO., LTD.**, Nanjing (CN)

(**) Term: **15 Years**

(21) Appl. No.: **29/912,126**

(22) Filed: **Sep. 14, 2023**

(30) **Foreign Application Priority Data**

Sep. 1, 2023 (CN) 202330566852.7

(51) **LOC (15) Cl.** **13-02**

(52) **U.S. Cl.**

USPC **D13/108**

(58) **Field of Classification Search**

USPC D13/103, 107, 108, 118, 119; D14/447, D14/251, 252, 253

CPC H02J 7/0044; H02J 7/0045; H02J 7/0069; H04B 1/3883

See application file for complete search history.

(57) **CLAIM**

The ornamental design for a wireless charger, as shown and described.

DESCRIPTION

FIG. 1 is a top perspective view of a wireless charger according to our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines indicate portions of the wireless charger that form no part of the claimed design.

1 Claim, 8 Drawing Sheets
